UNITED STATES PATENT OFFICE.

AUGUST G. LIEBMANN, OF CHICAGO, ILLINOIS.

COMPOSITE ADJUSTABLE RAIL-CHAIR.

1,279,722.

Specification of Letters Patent. Patented Sept. 24, 1918.

Application filed January 23, 1915, Serial No. 4,023. Renewed December 21, 1917. Serial No. 208,334.

To all whom it may concern:

Be it known that I, AUGUST G. LIEBMANN, a citizen of the United States, residing at Chicago, in the county of Cook and State 5 of Illinois, have invented certain new and useful Improvements in Composite Adjustable Rail-Chairs, of which the following is a specification.

This invention relates to railway track appliances and more particularly to rail chairs.

The object of the invention, generally stated, is to provide means for holding rails under all conditions of track and for use with any type of tie that may be considered 15 most economical from an engineering point of view.

At present, inferior grades of wood ties, previously subjected to treatment, are the most economic form of ties and, as it is 20 imperative that such ties be treated to resist decay, the present invention aims to provide a composite adjustable chair having an efficient fastening to obviate mechanical wear upon such treated or untreated ties.

25 The essential factors in a composite adjustable rail chair are as follows:

First, the elimination of mechanical wear. Second, efficiency in maintenance.

Third, the factor of resultant economy.

30 Fourth, the factor of safety.

Recognizing the need of a rail chair embodying, in a unitary structure, these essential factors, the invention comprehends the elimination of mechanical wear by providing 35 means for track gage variations on curves and tangents and rail surface variations in shimming without disturbance of the primary fastenings; for an increased area of plate support on the tie to prevent 40 cutting and crushing of said tie; for supporting the bed plate *per se* to prevent buckling and curling of the ends of the plate; for permanently supporting the bed plate on the tie to prevent abrasion; and for 45 eliminating respiking and consequent splitting of the tie.

The invention further comprehends an increased efficiency in maintenance by providing 50 means for expediting rail renewals of joined rails; for preventing the ties from skewing; for adapting the chair to all conditions of track; for permitting the use of the chair on new or old ties, and for preventing lost motion and change of adjustment.

Further to increase the factor of economy

by increasing the life of treated ties; by providing a chair of minimum weight and simplicity of parts; by permitting the chair to be attached to the tie at the treating 60 plant; by reducing the cost of maintenance through elimination of redriving and renewing spikes; and by providing a chair capable of being readily assembled and adjusted.

65 And further to insure the factor of safety by compensating for the recoil of the rails under stress; by supporting the rails against lateral, vertical and tipping thrusts; by the prevention of broken rails in a permanent 70 rail seat support; by holding the rails secure in shimmed positions; and by increasing the holding power of the plate fastenings to prevent rail displacements.

75 Further objects and advantages will appear in the following description, it being understood that various changes in form, proportions and minor details of construction may be resorted to within the scope of 80 the appended claims.

In the drawings:

Figure 1 illustrates a perspective view of an adjustable composite rail chair, embodying the present invention;

Fig. 2 is an end elevation, one of the 85 clamping members and its associated parts being shown in section;

Fig. 3 is a detail perspective view of one of the clamping members and screw caps, constituting the secondary fastening device 90 detached;

Fig. 4 is a transverse sectional view, showing a shim in position beneath the rail to adjust the rail for surface;

Fig. 5 is a top plan view of Fig. 1, the 95 screw cap on one side of the rail being removed to show the construction of the abutment;

Fig. 6 is an end elevation, showing the device used for joined rails and the clamping 100 members in contact with the angle bars of the rail;

Fig. 7 is a detail transverse sectional view, showing a modified form of abutment;

Fig. 8 is a similar view, showing the 105 adaptation of the chair to old ties;

Fig. 9 is an end view, showing the device in connection with a brace for preventing tipping thrust on curves;

Fig. 10 is a bottom plan view of the screw 110 cap and top plan view of the outer portion of the brace, showing the interlocking cor-

rugations for holding the brace in adjusted position;

Fig. 11 is a top plan view of Fig. 8 with the screw cap removed;

5 Fig. 12 is an end view, showing the device used in connection with a frog, the frog being shown in section;

10 Fig. 13 is an end view, showing the device used in connection with guard rails, the stock and guard rails being shown in section;

15 Fig. 14 is a top plan view of the spacing device shown in Fig. 13, the guard and stock rails being shown in section;

15 Fig. 15 is an end view, showing the fastening used in connection with switch points, the rail and switch point being shown in section.

Corresponding and like parts are referred 20 to in the following description and indicated in all the views of the drawings by the same reference characters.

Referring to the drawings, A represents a rail having a standard cross section, and B 25 a tie supporting the rail. Mounted upon the cross tie B, is a bed plate 5 preferably a rolled shape, although the plate may be cast or otherwise formed, if desired. The bed plate 5 is substantially rectangular in 30 shape, as shown, and preferably extends the entire width of the upper surface of the tie, the opposite longitudinal edges of the plate being bent downwardly to form depending flanges 6 which not only serve to reinforce 35 the plate, but by contact with the adjacent sides edges of the tie assist in preventing displacement of the plate on the tie. The extended area of the bed plate support serves to prevent cutting and crushing of 40 inferior wood ties, while the depending flanges 6, in conjunction with the clamping members, hereinafter referred to, prevent the bed plate from buckling and curling at its ends and also prevent splitting of the 45 cross tie.

Projecting upwardly from the bed plate 5, at the opposite ends thereof, and preferably formed integral therewith, are abutments 7, these abutments being hollow and 50 having their exterior walls preferably of octagonal shape to present a plurality of flat faces 8. Openings 9 are formed in the bed plate, one in alignment with the socket of each abutment for the reception of screw 55 spikes 10, said spikes constituting the primary fastening devices for securing the bed plate to the cross tie and having their upper portions provided with machine threads 11 and their lower portions formed with 60 screw threads 12 for engagement with the tie. Shoulders 13 are formed on the screw spikes at the junction of the threads, the lower face of each shoulder being convex and adapted to rest on a correspondingly con- 65 caved seat 14 formed in the upper surface

of the bed plate. The upper end of each spike is preferably formed with an angular head 15 so as to permit the screw spikes to be conveniently grasped by a wrench or other suitable tool.

70 Mounted on the abutments 7, are frusto-conical shaped clamping members 16, each having a central bore provided with a plurality of flat faces 17 corresponding in number to and adapted to engage the flat outer faces 8 of the abutments 7 for the purpose of holding the rail clamping members against rotation on the abutments after said clamping members have been actuated to adjust the rail vertically or laterally with respect to the bed plate. The lower face of each rail clamping member is provided with an eccentric portion 18 adapted to bear 75 against the adjacent longitudinal edge of the base flange of the rail A for shifting the rail laterally with respect to the bed plate when the clamping members are adjusted with respect to the abutments, the eccentric portion of each clamping member defining a circumferential clamping lip 19 80 for contact with the upper face of the base flange of said rail.

85 It will here be noted that the frusto-conical rail clamping members are disposed concentric with the abutments, while the portions 18 are disposed eccentric to said abutments. With such a construction, it will be readily seen that by moving the clamping members around the abutments, the rail may be adjusted laterally with respect to its seat for gage. It will, of course, be understood that in order to adjust the clamping members around the abutments, said clamping members must first be disengaged from the abutments, that is to say, 95 they must be elevated above the upper ends of the abutments and then turned until the desired flat faces of the abutments and clamping members register after which the clamping members are again positioned on the abutments and secured in adjusted position 100 by means of the cap screws.

105 Threaded on the screw spikes or primary fastening devices, are secondary fastening devices, preferably in the form of screw caps 20, each screw cap being provided with an interiorly threaded, depending cylindrical portion 21 for engagement with the machine threads on the adjacent spike and having a polygonal shaped head and a circumferential flange 22 adapted to bear against the upper flat face of the adjacent rail clamping member so that when the screw caps are adjusted home, the flanges 22 will 115 bear against the members 16 and clamp the latter in engagement with the base flange of the rail.

120 It will here be noted that the upper face of each clamping member 16 extends a slight distance above the upper surface of the ad- 130

jacent abutment so as to cause the flange 22 to bear directly on the rail clamping member and through the medium of said member transmit a clamping action to the base flange of the rail. It will also be noted that the flange 22, by contact with the upper face of the clamping member, compensates for recoil of the rail under stress. Should the screw cap 20, for any reason, become loose, the rail clamping member will have a slight vertical movement on the adjacent abutment and thus prevent fracture of the base flange of the rail.

As the clamping members are substantially frusto-conical in shape, the outer faces of said clamping members will form, in effect, skidways and thus expedite rail renewals with joined rails, it being merely necessary to remove one of the clamping members 16 and then move the line of joined rails laterally from engagement with the lip of the other clamping member when said joined rails may be readily removed, the inclined faces of the clamping members forming, in effect, skidways, as before stated. It will further be noted that the screw caps 20 not only serve to clamp the members 16 in engagement with the base flange of a rail, but also serve to house and protect the screw spikes or primary fastenings and resist the action of the wheels of derailed cars so as to prevent injury to the primary fastening devices. The rail clamping members are preferably disposed in staggered relation on the bed plate and are so constructed as to allow for longitudinal expansion and contraction of the rails. The primary fastening devices in conjunction with the flanges 6 of the bed plate, serve to prevent ballast from working under the bed plate and destroying the bed plate support. The primary fastening devices also prevent buckling or curling of the ends of said bed plate.

In order to adjust the rail laterally on the bed plate for gage, it is merely necessary to remove the screw caps 20 and position one of the rail clamping members on the adjacent abutment with the large portion of the eccentric bearing against the base flange of the rail on one side thereof, and with the short portion of the eccentric of the other clamping member bearing against the base flange of the rail on the other side of said rail, after which the screw caps are threaded on the screw spikes and adjusted home, which clamps the members 16 in engagement with the base flange of the rail and effectually prevents accidental displacement of said rail. It will be understood that by moving the rail clamping members 16 to different positions of adjustment, around the abutments, the rail may be shifted laterally in either direction for gage, as required. In order to adjust the rail vertically for surface, the screw caps are rotated to elevate

the same and a shim 23 placed beneath the rail, after which the screw caps are tightened, as best shown in Fig. 4 of the drawings. If desired, the shim 23 may extend beneath the adjacent rail clamping members 70 so that when the screw caps are tightened, said rail clamping members will prevent accidental displacement of the shim.

Attention is here called to the fact that by reason of the large radius of the eccentric portions 18 of the rail clamping members, an extended bearing surface is presented to the base flange of the rail, thus preventing the ties from skewing, and further inasmuch as the members 16 bear against the flange of 80 the rail at diagonally opposite points, said members will assist in supporting the rail against vertical, lateral and tipping thrust. The particular form of fastening disclosed in this application is of minimum weight 85 and of few parts and is so constructed as to prevent rattling, due to wear of the parts or lost motion with consequent change of adjustment. The rail clamping members are interchangeable and may be moved in either 90 direction to different positions around the abutments to effect the adjustment of the rail for gage. When the chair is made of a casting, a copper content will preferably be added to the material so as to cause the fastening to resist rust and thus prolong the life thereof in saline soils and withstand the drippings from refrigerator cars.

In Fig. 6 of the drawings, the rail chair is shown in connection with joined rails, the 100 construction and operation of the device being otherwise the same as that shown in Fig. 1 of the drawings, with the exception that the lips 19' of the rail clamping members engage angle bars 24, instead of bearing directly on the base flange of the rail and in that the eccentrics 18' are of greater depth 105 to permit the lips 19' to bear against said angle bars.

A further modification is illustrated in 110 Fig. 7 of the drawings, in which the abutments 7', instead of being rolled or cast with the body of the bed plate, are formed separately and seated in suitable openings 25 formed in said bed plate. In this form of the device, the abutments 7' are provided with laterally extending circumferential flanges 26 which fit in countersunk portions 27 in the upper surface of the bed plate so as to prevent accidental displacement of the abutments and at the same time present a smooth surface for the rail clamping member. It will of course be understood that the abutments 7' may be secured within the 115 openings 25 in any suitable manner.

The device shown in Fig. 1 is particularly adapted for attachment to new ties. The chair, however, may be applied with equally good results to old or spike killed ties, and in Figs. 8 and 11 of the drawings, there is 120

illustrated a structure for this purpose. When the chair is used on old or spike killed ties, the bed plate is preferably formed with a plurality of square openings 28 and 29, 5 the openings 29 being adapted to receive screw bolts 30, the heads of which extend through the openings 29 and are preferably countersunk in the upper surface of the tie. Ordinary spikes are preferably driven in 10 the openings 28 for the purpose of holding the chair securely in position on the tie. As the openings 28 and 29 will be spaced from the spike killed portion of an old tie, it is obvious that a fresh or unmutilated area of 15 the tie will be presented for the driving of the ordinary spikes, when using this type of the invention, as best shown in Fig. 11 of the drawings.

Where the fastening is used on curves, a 20 brace 31 is preferably employed, the inner end of said brace being provided with a head 32 for contact with the lower face of the head of the rail and the base flange thereof, respectively, and the outer end of the brace 25 being interposed between the upper face of the rail clamping member and the lower face of the flange of the screw cap or secondary fastening. In order to cause the brace to bear against the rail and prevent displacement 30 of the brace, when the rail is adjusted laterally for gage, the lower face of the flange of the screw cap is preferably formed with one or more ribs or corrugations 33 adapted to enter corresponding grooves 34 35 formed in the upper face of the brace, there being a slot 35 formed in the brace adapted to receive the cylindrical portion of the screw cap and permit adjustment of the brace to accommodate the rail. This brace 31, as 40 will be understood, prevents tipping thrust of the rail on curves.

In Fig. 12 of the drawings, the improved fastening is shown in connection with a conventional form of frog, while in Figs. 13 45 and 14, the fastening is shown for clamping a stock and guard rail, respectively. The fastening device may be employed with equally good results for use in connection with switch points and in Fig. 15 of the 50 drawings, the fastening is shown supported on a base plate and engaging the stock rail adjacent a switch point.

While the abutments and sockets of the rail clamping members are shown as being 55 of octagonal formation, it will of course be understood that they may be square, hexagonal or of any other angular shape or that other means may be employed for preventing rotation of the clamping members on the 60 abutments after adjustment for gage, without departing from the spirit of the invention.

From the foregoing description, it will be seen that the improved chair provides for 65 gage variations on curves and tangents; for

the restoration of gage without respiking; and for rail surface variations, low joints, kinks, shimming and the like, without re-spiking.

The chair and fastener forming a part 70 thereof is so constructed that it will effectually eliminate mechanical wear to cross ties, and consequently prolong the life of treated or untreated ties by providing for lateral and vertical adjusting of the rail for curves 75 or tangents without the necessity of disturbing the primary fastening devices or respiking or shifting the bed plate of the chair on the tie to effect such adjustment.

Having thus described the invention, what 80 is claimed as new is:

1. A rail chair including a bed plate and fixed upstanding abutments, and rail clamping members movable to different positions around the abutments for holding a rail in 85 lateral and vertical adjustment with respect to the bed plate.

2. A rail chair including a bed plate and abutments of angular formation, and rail clamping members bearing against and movable around the abutments for holding a rail in different positions of lateral and vertical 90 adjustment with respect to the bed plate.

3. A rail chair including a bed plate and abutments of angular formation, and rail clamping members fitted over the abutments and having eccentric portions movable into engagement with a rail for holding the rail in different positions of lateral and vertical 95 adjustment with respect to the bed plate. 100

4. A rail chair including a bed plate and abutments of angular formation, and rail clamping members concentrically mounted on the abutments and having eccentric portions movable into engagement with a rail for holding the rail in different positions of lateral and vertical adjustment with respect to the bed plate. 105

5. A rail chair including a bed plate and abutments of angular formation, rail clamping members fitting the abutments and movable to different positions around said abutments for holding a rail in lateral and vertical adjustment with respect to the bed plate, and means for forcing the clamping members 110 into engagement with the rail. 115

6. A rail chair including a bed plate and an abutment having an angular face, and a rail clamping member concentrically mounted on the abutment and having an angular 120 portion for engagement with the angular face of the abutment and an eccentric portion movable into engagement with a rail for holding the rail in adjusted position.

7. A rail chair including a bed plate and an abutment having an angular face, and a rail clamping member movable to different positions around the abutment and having a correspondingly angular portion for engagement therewith. 125

8. A rail chair including a bed plate and abutments, rail clamping members bearing against and movable to different positions around the abutments for holding a rail in different positions of lateral and vertical adjustment with respect to the bed plate, primary fastening devices housed within the abutments and piercing the bed plate, and secondary fastening devices engaging the primary fastening devices.
10. A rail chair including a bed plate and abutments, rail clamping members concentrically mounted on the abutments and having eccentric portions movable into engagement with a rail for holding said rail in different positions of lateral and vertical adjustment, and primary fastening devices extending through the abutments and piercing the bed plate.
20. A rail chair including a bed plate and abutments, primary fastening devices extending through the abutments and piercing the bed plate for securing the bed plate to a cross tie, and rail clamping members disposed in contact with and movable to different positions around the abutments for shifting the rail laterally with respect to the bed plate without disturbing the primary fastening devices.
30. A rail chair including a bed plate and abutments, rail clamping members movable to different positions around the abutments, primary fastening devices extending through the abutments and bed plate for engagement with a cross tie, and secondary fastening devices engaging the primary fastening devices and forming a housing for the latter.
40. A rail chair including a bed plate and abutments, rail clamping members bearing against and movable to different positions around the abutments for shifting a rail laterally with respect to the bed plate, and means exerting a downward pressure on the clamping members for holding the rail on the bed plate or on a shim in different positions of adjustment.
50. A rail chair including a bed plate and abutments, interchangeable clamping members adapted to fit over the abutments and each provided with an eccentric portion movable into engagement with a rail for holding the rail in different positions of lateral and vertical adjustment.
55. A rail chair including a bed plate having upstanding abutments disposed in staggered relation and each having an angular outer face, and rail clamping members having sockets provided with angular faces fitting around the abutments and engaging the angular faces of said abutments, each clamping member being provided with an eccentric portion for engagement with a rail.
60. In a rail chair, a bed plate having an upstanding abutment of octagonal cross sec-
- tion, and a rail clamping member having a socket of corresponding shape fitting over the abutment and provided with an eccentric portion movable into engagement with a rail, said rail clamping member being movable to different positions around the abutment with a step by step motion to present different portions of the eccentric to the rail.
65. In a rail chair, a bed plate and an abutment, a substantially frusto-conical rail clamping member bearing against and movable to different positions around the abutment, and an eccentric portion formed on the rail clamping member.
70. In a rail chair, a bed plate having an abutment, a rail clamping member mounted on and movable to different positions around the abutment, a primary fastening device extending through the abutment and bed plate for engagement with a cross tie, and a screw cap having a threaded portion for engagement with the primary fastening device and provided with a lateral flange adapted to bear against the adjacent face of the rail clamping member.
75. In a rail chair, a bed plate having an abutment, a rail clamping member mounted on and movable to different positions around the abutment, a primary fastening device extending through the abutment and bed plate for engagement with a cross tie, and a screw cap having a threaded portion for engagement with the primary fastening device and provided with a lateral flange adapted to bear against the adjacent face of the rail clamping member.
80. In a rail chair, a bed plate having a hollow upstanding abutment, there being an opening formed in the bed plate at said abutment, a rail clamping member bearing against the abutment and movable to different positions around the same, a screw spike extending through the opening in the bed plate and provided with a shoulder for contact with the bed plate, and a screw cap cooperating with the rail clamping member engaging the screw spike and forming a housing for the latter.
85. In a rail chair, a bed plate having depending longitudinally disposed flanges for engagement with a cross tie and provided with upstanding hollow abutments arranged in staggered relation, rail clamping members disposed in contact with the abutments and movable to different positions around the same, primary fastening devices extending through the abutments, said rail clamping members being each provided with an eccentric portion for engagement with a rail, and secondary fastening devices engaging the primary fastening devices and bearing against the rail clamping members for forcing the latter downwardly.
90. In a rail chair, a bed plate having a hollow upstanding abutment of octagonal cross section, a substantially frusto-conical rail clamping member of greater height than the abutment fitting over and movable to different positions around said abutment, a screw spike disposed within the abutment and piercing the bed plate for engagement with a cross tie, and a screw cap engaging threads on the head of the screw spike and bearing against the upper face of the rail clamping member.
105. In a rail chair, a bed plate having a hollow upstanding abutment of octagonal cross section, a substantially frusto-conical rail clamping member of greater height than the abutment fitting over and movable to different positions around said abutment, a screw spike disposed within the abutment and piercing the bed plate for engagement with a cross tie, and a screw cap engaging threads on the head of the screw spike and bearing against the upper face of the rail clamping member.
110. In a rail chair, a bed plate having a hollow upstanding abutment of octagonal cross section, a substantially frusto-conical rail clamping member of greater height than the abutment fitting over and movable to different positions around said abutment, a screw spike disposed within the abutment and piercing the bed plate for engagement with a cross tie, and a screw cap engaging threads on the head of the screw spike and bearing against the upper face of the rail clamping member.
115. In a rail chair, a bed plate having a hollow upstanding abutment of octagonal cross section, a substantially frusto-conical rail clamping member of greater height than the abutment fitting over and movable to different positions around said abutment, a screw spike disposed within the abutment and piercing the bed plate for engagement with a cross tie, and a screw cap engaging threads on the head of the screw spike and bearing against the upper face of the rail clamping member.
120. In a rail chair, a bed plate having a hollow upstanding abutment of octagonal cross section, a substantially frusto-conical rail clamping member of greater height than the abutment fitting over and movable to different positions around said abutment, a screw spike disposed within the abutment and piercing the bed plate for engagement with a cross tie, and a screw cap engaging threads on the head of the screw spike and bearing against the upper face of the rail clamping member.
125. In a rail chair, a bed plate having a hollow upstanding abutment of octagonal cross section, a substantially frusto-conical rail clamping member of greater height than the abutment fitting over and movable to different positions around said abutment, a screw spike disposed within the abutment and piercing the bed plate for engagement with a cross tie, and a screw cap engaging threads on the head of the screw spike and bearing against the upper face of the rail clamping member.

21. A rail chair including a bed plate having staggered abutments of angular formation, and laterally and vertically adjustable members having corresponding angular portions coöoperating with the abutments for holding a rail in different positions of adjustment with respect to the bed plate.
22. A rail chair including a bed plate having abutments, laterally and vertically adjustable rail clamping means coöoperating with the abutments for holding a rail in different positions of adjustment with respect to the bed plate, and primary fastening means disposed within the abutments.
23. A rail chair including a bed plate having spaced upstanding hollow abutments, laterally and vertically adjustable rail clamping means coacting with the abutments for holding a rail in different positions with respect to the bed plate, and primary and sec-

ondary fastening devices for the rail clamping means, the primary fastening devices being housed within the abutments and the secondary fastening devices serving to protect the primary fastening devices. 25

24. A universal composite rail chair including a bed plate having staggered abutments of angular formation, and laterally and vertically adjustable rail holding means fitting over and coöoperating with the abutments and adapted to hold a rail in different positions of adjustment on ties, at or between joints or with frogs, switches or guard rails. 30

In testimony whereof I affix my signature in presence of two witnesses.
